INFANT'S DRESSING TABLE

Filed Sept. 22, 1927

Fig. 1.

UNITED STATES PATENT OFFICE

REINHOLD W. MARQUARDT, OF MILWAUKEE, WISCONSIN

INFANT'S DRESSING TABLE

Application filed September 22, 1927. Serial No. 221,156.

My invention relates to improvements in infant's dressing tables.

It is an object of my invention to provide a folding dressing table provided with a top which may be easily removed to be washed, repaired or replaced. It is another object of my invention to provide a sturdy foldable dressing table which may be easily and compactly folded for storage.

10 In the drawings:

Figure 1 is a side view of my dressing table unfolded for use.

Figure 2 is an isometric view of my dressing table top with its rods.

15 Figure 3 is a view of one of the bracket members for supporting a rail.

Figure 4 is another view of the same bracket showing the rod in position.

I am aware that infants' dressing tables of 20 the general type set forth in the drawings are in common use. However, much difficulty in keeping the table top sanitary and clean is found in the well known type, and I have therefore provided means for permitting easy 25 removal of the cloth or canvas comprising the top so that it may be washed, repaired or replaced with a new one.

The frame of my table comprises two pair of crossed legs such as the two crossed as indicated at 5 and 6 in Figure 1, the one set of crossed legs being spaced from the other by a strut 7, which provides a pivot about which the legs 5 and 6 may be folded. The spread of the legs in open position is predetermined by a foldable link 8, which prevents the table from collapsing even when the top 10 is removed. Rails 12 connecting the top of the legs in either side of the table complete the unitary table body on which my improved 40 top construction including the rods 9 is removably positioned.

Each of the rods 9 comprise a stick which is turned down at each end to provide a trunnion 13 receivable into the bracket 11 as indicated in Figure 4 wherein I have shown my preferred method of mounting my bracket to provide means for bracing the entire table. Obviously the arm 14 on the bracket will form an adequate reinforcement and stiffener between the legs and the rails 12, and the

flanged pocket 15 will receive the trunnions 13.

The canvas or other flexible material of which the top is made is provided at each side with a wide hem 16 heavily stitched and open 55 at the ends to receive the rods 9. When the rods have been placed in the hem the canvas 10 is placed over the top of the partially folded table, the rods are swung outwardly beyond the rails and received beneath the 60 rails into the bracket pockets 15 thereby locking the trunnions 13 into the pockets under tension of the canvas when the table is opened to its widest position under restraint of the link 8.

65 Removal of the top from its support is quickly accomplished by collapsing the link 8 and drawing the rails toward each other, the looseness of the canvas then permitting withdrawal of the rods from their secured 70 position. Each of the rods may then be slipped from the hems of the canvas to leave the canvas free for washing or for repair. Obviously, new canvases may be supplied and a number of canvases may be made available 75 for quick change if desired.

It is particularly to be noted that the brackets 11 are closely adjacent the top rails 12 of the table frame so that when rods 9 are in place the flexible table top will be snubbed 80 short about the rails. This construction not only is stronger than any alternative arrangement but also renders accidental disengagement of the parts impossible since the rods lie behind the rails and there is no exposed 85 length of canvas below the rails against which the knee of an attendant might strike to disengage the retaining rod.

I claim:

1. A collapsible table frame provided with spaced rails, upwardly opening inwardly inclined pockets immediately beneath the rails, a table top provided with rods removably positioned in the pockets for free disengagement therefrom when the table is in partially 95 folded position, and locked by the tension of the table top when the table frame is in distended position.

2. A table frame including cross legs and rails connecting the legs, brackets with in- 100

wardly opening sockets upon the table frame and providing members to brace and support the rails, a top extending about said rails and provided with rods detachably positioned in the sockets and holding said top about the rails against said members, said rods being receivable in the inwardly opening sockets when the frame is collapsed upon its cross legs and retained in the sockets by the tension of the top when the table frame is extended in operative position.

3. In combination, a collapsible frame provided with top supporting rails, a flexible top provided with attaching rods and adapted to be stretched between the rails when the table is in extended position, and rod receiving sockets opening in a direction such that the tension of the top between the rails holds the rods within the sockets in frame extended position.

4. The combination with a frame including spaced rails and supports therefor, of a flexible top provided with a marginal receiving loop, a rod receivable in the loop and extending therefrom to provide a free end, a bracket provided with a rod receiving socket secured to said support adjacent said rail whereby to receive the end of the rod and retain the top about a rail.

5. The combination with a support and a rail extending therefrom, of a bracket secured in the angle between the support and said rail, said bracket being provided with an upwardly extending slot; and a flexible top to be extended over the rail and provided with a member receivable in the slot to prevent removal of the top from its position about the rail.

REINHOLD W. MARQUARDT.
